MOP AND BRUSH CLEANING DEVICE**Gregory J. Campbell, Freeport, Ill., assignor to
William T. Neiman, Freeport, Ill.****Application February 18, 1957, Serial No. 640,853****4 Claims. (Cl. 15—142)**

This invention relates to a device for cleaning dust 15 mops, brushes and the like.

The general object of this invention is to provide a device for use within the home for removing dust and lint from mops and brushes and which confines the removed dust and lint in a receptacle for subsequent disposal.

Another object of this invention is to provide a device for cleaning mops and brushes which includes an open top receptacle having racks therein for cleaning the mop as the latter is moved within the receptacle and which rack is so arranged as to deflect the dust and lint away from the open top of the receptacle to thereby prevent the escape of the dust through the open top.

A further object of this invention is to provide a mop cleaning device including a receptacle having mop cleaning racks therein arranged to circulate and direct the flow of air through the bristles on the mop or brush, as the latter is moved along the rack in the receptacle, to provide improved cleaning of the mop or brush.

Yet another object of this invention is to provide a mop cleaning device of simple and economical construction and which may be readily assembled and disassembled for cleaning.

These, together with various ancillary objects and advantages of this invention will be more readily appreciated as the same becomes better understood by reference to the following detailed description when taken in connection with the accompanying drawing wherein:

Figures 1 and 2 are transverse sectional views through the mop cleaning device and illustrating the operation of the latter in cleaning a mop;

Fig. 3 is a side elevational view of the mop cleaning device with the side of the receptacle broken away to illustrate details of construction; and

Fig. 4 is a perspective view of the cleaning device and illustrating the mop therein.

Referring more specifically to the accompanying drawings, the mop cleaning device includes a receptacle having opposed side walls 10, end walls 11 and a bottom wall 12. The receptacle is open at the top thereof and has a carrying handle or bail 13 attached by means of brackets 14 on the end walls 11.

A pair of spaced mop cleaning racks 21 are disposed within the receptacle, and, as shown in the drawings, each include a pair of upstanding members 22 having a flange 22a thereon adapted to abut against the end walls 11. A plurality of horizontally disposed louvers 24 are attached to, or formed integrally with the upstanding members 22 on each rack, which louvers are inclined in a direction transverse to their length to extend downwardly and inwardly of the receptacle, as best shown in Figures 1 and 2. In the specific embodiment shown, the louvers 24 are formed separate from the upstanding members 22 and have the ends thereof bent to extend in a plane inclined to the plane of the louvers, which ends are secured to the respective upstanding member 22, as by rivets 25. An imperforate panel 26 is provided

2

adjacent the upper ends of each of the upstanding members 22 and, in the specific form illustrated, the imperforate panel is formed separate from the upstanding members and rigidly secured to the latter as by fasteners 27. The imperforate panel extends vertically upwardly from a point spaced above the uppermost one of the louvers 24 and has a portion 28 on the upper end thereof which extends outwardly and terminates in a downwardly extending flange 29. The outwardly extending portion 28 is arranged to span the space between the panel 26 and the side wall of the receptacle and may conveniently be inclined upwardly and outwardly from the top of the respective panel, as shown in Figures 1 and 2, to facilitate guiding of the mop into the space between the racks 21. The depending flange 29 is arranged to engage the side wall 10 of the receptacle to form a seal therewith and prevent the escape of dust therebetween.

Panels 31 are provided adjacent the lower ends of the racks and extend between the upstanding members 22, which lower panels have an opening 32 adjacent the lower end thereof to permit the circulation of air therethrough. The racks are slidable into and out of the receptacle and are maintained in proper spaced relation to each other by a plurality of cross pieces 34, herein shown in the form of straps which extend between the racks, at a point spaced above the bottom of the receptacle, to limit downward movement of the mop. The cross pieces have U-shaped end portions 35 provided thereon adapted to receive the upper edge of the lower panel 31 and fasteners 36 extend through the U-shaped members and through the panel 31 to secure the straps 34 to the racks and thereby maintain the latter in proper spaced relation. As is apparent from Figures 1 and 2, the flanges 22a on the upstanding members 22 extend outwardly beyond the outer edges of the louvers 24 and thereby assure that the outer edges of the louvers are spaced from the side walls of the receptacle, when the rack is assembled therein, to permit free circulation of air between the louvers and the adjacent side walls of the receptacle.

In order to produce proper operation of the dust mop cleaning device, it is essential that the dimensions of the mop be correlated with those of the cleaning device so that the length of the mop is substantially equal to the spacing between the end walls 11 of the receptacle and the width of the mop is such as to be snugly received between the racks 21. As best shown in Figure 4, the mop head 41 substantially completely fills the space between the walls 11 and between the racks 21, as the mop is moved upwardly and downwardly between the racks. In addition, the mop head 41 is preferably so formed that the bristles or thrums thereof extend generally in a direction transverse to the direction of movement of the mop in the cleaning device. A handle 43 is attached, as by a coiled ferrule 44, to the mop head.

It is thought that the operation of the device will be readily understood by reference to Figures 1 and 2. The mop head 41 is inserted into the cleaning device and is guided by the portions 28 to a position between the racks 21. As the mop head 41 is moved downwardly, the bristles or thrums thereon engage the louvers 24 and are thereby subjected to a "beating" action which tends to loosen the dirt from the thrums. In addition, since the mop head substantially completely fills the space between the end walls 11 of the receptacle and the racks 21, the air within the receptacle, between the racks and below the mop head, is displaced therefrom as the mop head is moved downwardly. Some of the air is forced outwardly between adjacent louvers and flows across the thrums or bristles of the mop to aid in cleaning the latter. Some of the air below the mop is forced downwardly and then passes upwardly through

the flow passage formed between the racks and the adjacent ones of the side walls 10. Since the louvers 24 are inclined downwardly and inwardly, the upwardly flowing stream of air and the dust carried therein is deflected by the louvers toward the adjacent side wall of the receptacle and is thereby effectively prevented from passing into the space between the racks and above the mop head 41. The air instead passes upwardly into the confined space defined by the imperforate top panel 26, the outwardly extending portion 28, and the adjacent side wall 10 of the receptacle.

When the mop head 41 is thereafter moved upwardly, in the direction indicated by the arrow in Figure 2, the louvers 24 are again effective to produce a "beating" action on the bristles of the mop. In addition, there is a reduction in pressure below the mop head 41, and between the racks 21, as the mop head is moved upwardly. Air then passes downwardly in the passages between the racks and the adjacent side walls and a portion of this air is deflected inwardly by the louvers to pass through the bristles of the mop 41, as indicated by the arrows in Figure 2. This flow of air through the bristles of a mop also aids in cleaning the same. In order to thoroughly clean the mop, the latter is moved rapidly upwardly and downwardly between the racks, a number of times, before removing the mop from the cleaning device.

I claim:

1. A dust mop cleaner comprising a receptacle having spaced side walls, opposed end walls, a bottom wall and an open top, a pair of vertically extending mop cleaning racks disposed in said receptacle in spaced relation to each other and in spaced relation to said side walls, said racks extending between said end walls and each including a plurality of vertically spaced horizontally extending louvers each inclined in a direction transverse to the length thereof to extend downwardly and inwardly of the receptacle, the inner edges of said louvers being spaced apart to snugly receive a mop therebetween whereby the air between the racks and below the mop is alternately forced outwardly from between the racks and then drawn inwardly as the mop is moved downwardly and upwardly between the racks, the outer edges of said louvers being spaced from the adjacent side walls an appreciable distance to provide a flow passage therebetween to permit the air which is forced outwardly from between the racks, as the mop is pushed downwardly, to pass upwardly between the racks and the adjacent one of the side walls and to permit air to pass downwardly into the space below the mop as the latter is moved upwardly, said louvers being operative to deflect the upwardly flowing air toward the adjacent side wall and to deflect the downwardly flowing air through the tufts of the mop to aid in cleaning the same, said racks each including an imperforate panel extending between the end walls of the receptacle adjacent the upper end of each rack and in spaced relation to the adjacent side walls of the receptacle, and means extending between the upper edges of said imperforate panels and the adjacent side walls to seal the space therebetween.

2. A dust mop cleaner comprising a receptacle having spaced side walls, opposed end walls, a bottom wall and an open top, a pair of vertically extending mop cleaning racks removably disposed in said receptacle, said racks extending between said end walls and each

including a plurality of vertically spaced horizontally extending louvers each inclined in a direction transverse to the length thereof to extend downwardly and inwardly of the receptacle, said racks having vertically disposed flanges on opposite ends thereof extending in a direction transversely to said racks into engagement with the side walls of the receptacle to maintain the outer edges of said louvers on the racks spaced from said side walls an appreciable distance sufficient to provide an open air circulating passage therebetween, cross members attached to said racks above the bottom of said receptacle and extending between said racks to maintain said racks in spaced relation to each other, and means defining a closure between the upper ends of said rack and the adjacent side wall of said receptacle.

3. A dust mop cleaner comprising a receptacle having spaced side walls, opposed end walls, a bottom wall and an open top, a pair of vertically extending mop cleaning racks removably disposed in said receptacle, said racks extending between said end walls and each including a plurality of vertically spaced horizontally extending louvers each inclined in a direction transverse to the length thereof to extend downwardly and inwardly of the receptacle, said racks having vertically disposed flanges on opposite ends thereof extending in a direction transversely to said racks into engagement with the side walls of the receptacle to maintain the outer edges of the louvers on the racks spaced from said side walls an appreciable distance sufficient to provide an open air circulating passage therebetween, cross members attached to said racks above the bottom of said receptacle and extending between said racks to maintain said racks in spaced relation to each other, an imperforate panel extending between the flanges on each of said racks adjacent the upper ends of said racks, said panels being spaced from the adjacent side wall of said receptacle, and a top flange on each of said racks extending between the upper edge of each panel and the adjacent side wall of the receptacle to seal the space therebetween.

4. A dust mop cleaner comprising a receptacle having spaced side walls, end walls, a bottom wall and an open top, a pair of vertically disposed imperforate panels in said receptacle adjacent the top thereof, said panels being spaced from the adjacent side walls and from each other to receive a mop head therebetween, means extending between the upper edges of said panels and said side walls to close the space therebetween, a set of vertically spaced horizontally extending louvers disposed below each of said panels with each louver inclined in a direction transverse to the length thereof to extend downwardly and inwardly of the receptacle, the outer edges of each of the louvers being spaced from the adjacent side walls of the receptacle to define a passage therebetween to permit free circulation of air between the louvers and the adjacent side walls as a mop head is moved alternately upwardly and downwardly in the space between the sets of louvers.
